(57) **CLAIM**

The ornamental design for a pipe gasket, as shown and described.

DESCRIPTION

FIG. 1 is a perspective view of the pipe gasket of the invention showing the overall profile of the gasket;

FIG. 2 is a top view of the pipe gasket of FIG. 1, the bottom view being a mirror image thereof;

FIG. 3 is a side view of the pipe gasket of FIG. 1; and, FIG. 4 is a cross sectional view of the pipe gasket showing the detail of the external surfaces of the gasket, taken along line 4—4 as shown in FIG. 1.
